(Cl. D34—5)

To all whom it may concern:

Be it known that we, Thomas O. Brandon, Walter B. Gerould, James M. Long and Luke J. Smith, Jr., each a citizen of the United States, residing respectively, at Cucamonga, county of San Bernardino, and State of California, Longmeadow, county of Hampden, and State of Massachusetts, South Hadley Center, county of Hampshire, and State of Massachusetts, and East Longmeadow, county of Hampden, and State of Massachusetts, have invented a new, original, and ornamental Design for Grip for Golf Clubs and the like Athletic Implements, of which the following is a specification, reference being had to the accompanying drawing, forming part thereof.

Figure 1 is a side elevational view of the grip

for golf clubs and the like athletic implements.

Fig. 2 is a view taken along lines 2—2 of Fig. 1 showing the arrangement of the longitudinal slots around the grip.

Fig. 3 is a view taken along lines 3—3 of Fig. 1.

We claim:

The ornamental design for a grip for golf clubs and the like athletic implements, as shown.
